STRIPPER ELEMENT FOR MEAT SKINNING MACHINES

Donald L. Beasley, Des Moines, Iowa, assignor to Town-
send Engineering Company, Des Moines, Iowa

Filed Apr. 21, 1972, Ser. No. 246,505

Term of patent 14 years

Int. Cl. D15—99

U.S. Cl. D55—1 E

FIG. 1 is a frontal perspective view of a stripper element for meat skinning machines showing my new design;

FIG. 2 is a rear elevational view thereof;

FIG. 3 is a side elevational view thereof as seen from the lefthand side of FIG. 2;

FIG. 4 is a side elevational view as seen from the righthand side of FIG. 2;

FIG. 5 is a top plan view; and

FIG. 6 is a bottom plan view.

I claim:

The ornamental design for a stripper element for meat skinning machines, substantially as shown.
